UNITED STATES PATENT OFFICE.

MAXIME CHEVRIER, OF HARRISVILLE, NEW YORK, ASSIGNOR TO THE
UNIVERSAL WOODEN WARE COMPANY, OF SAME PLACE.

DESIGN FOR A WOODEN DISH.

SPECIFICATION forming part of Design No. 33,217, dated September 18, 1900.

Application filed June 20, 1900. Serial No. 21,018. Term of patent 14 years.

To all whom it may concern:

Be it known that I, MAXIME CHEVRIER, a subject of the Queen of Great Britain, residing at Harrisville, in the county of Lewis and State 5 of New York, have invented and produced a new and useful Design for a Wooden Dish, of which the following is a specification, reference being had to the accompanying drawings, forming a part thereof.

Figure 1 is a plan view of a wooden dish shaped according to my new design. Fig. 2 is a sectional view thereof, taken on the line 2 2 of Fig. 1; and Fig. 3 is a transverse sectional view thereof, taken on the line 3 3 of 5 Fig. 1.

As shown in the drawings, my design is characterized by a central partially cylindrical portion A, having straight sides *a* and curved or partially-oval end portions B.

The longitudinal section of a dish embody-

ing my design is substantially trapezoidal or has the shape of a four-sided figure, the longer sides of which are parallel, as shown in Fig. 2, and the transverse section thereof is substantially segmental or has the shape of a 25 figure bounded by an arc of a circle and its chord, as shown in Fig. 3.

Having described my invention, what I claim as new, and desire to secure by Letters Patent of the United States, is—

30

The design for a wooden dish as herein shown and described.

In testimony whereof I have hereunto set my hand in the presence of two subscribing witnesses.

MAXIME CHEVRIER.

Witnesses:

FREDERIC P. CLEMENT,
FRANK HUMES.
